UNITED STATES PATENT OFFICE.

FREDERICK MERTSHEIMER, OF KANSAS CITY, MISSOURI.

STEAM-EXHAUST NOZZLE.

1,155,362.

Specification of Letters Patent.

Patented Oct. 5, 1915.

Application filed March 19, 1915. Serial No. 15,662.

To all whom it may concern:

Be it known that I, FREDERICK MERTSHEIMER, a citizen of the United States, residing at Kansas City, in the county of 5 Jackson and State of Missouri, have invented certain new and useful Improvements in Steam-Exhaust Nozzles; and I do declare the following to be a full, clear, and exact description of the invention, such as will 10 enable others skilled in the art to which it appertains to make and use the same, reference being had to the accompanying drawings, and to the letters and figures of reference marked thereon, which form a part 15 of this specification.

My invention relates to steam exhaust nozzles, and more particularly to nozzle tips in use in locomotive or other steam engines wherein steam is used to create a draft; the 20 principal object of the invention being to provide a nozzle with an adjustable tip and means for operating or regulating the tip from the engine cab, whereby the fireman may secure a desired blast through the grates.

25 In accomplishing this object I have provided improved details of structure, the preferred forms of which are illustrated in the accompanying drawings, wherein:

Figure I is a perspective view of an adjustable nozzle tip constructed according to 30 my invention. Fig. II is a front view of the device and a portion of the smoke arch, showing one of the operating rods extending through the arch. Fig. III is a side view of 35 the nozzle showing the operating rod and its mounting on the engine cab. Fig. IV is a plan view of the nozzle tip.

Referring more in detail to the drawings:—1 designates the upper portion of an 40 exhaust nozzle of the type used in the ordinary locomotive, and which is located in the smoke arch directly below the stack (not shown) and adapted for directing a column of exhaust steam through the stack to create 45 a partial vacuum through the arch and produce a forced draft through the fire.

Formed integrally with and extending laterally from the nozzle is an annular flange 2, and seated on said flange is a nozzle tip 3 comprising a slightly tapered cylindrical portion 4 conforming in size with the upper portion of the nozzle 1, and having side lugs 5 provided with apertures for receiving bolts 6 whereby the tip is secured 55 to the flange 2.

Projecting laterally from opposite sides of

the tip 3 and formed integrally therewith are wings 7 which extend throughout the height of the tip and have longitudinal grooves therein opening through the outer edges and both ends of the wings to provide guides or slideways 8 for the posts 9, which are adapted for free travel therein; each of the posts 9 being beveled outwardly from its lower inner corner in order to form a wedge face that will force cinders, or the like, that may accumulate in the bottom of the wing sockets or guideways 8, outwardly from the guideways and keep the latter clear to prevent the cinders from interfering with the full vertical travel of the posts. Each of the posts 9 is also provided with grooves 10 in its side faces and the grooves extend throughout the length of the post to provide channels through which fine cinders or dust that may accumulate at the bottom of the socket, within which the post is movable, may be drawn out by the forced draft in the nozzle to clean the socket and scour the same to insure free vertical movement of the post.

The posts 9, which are arranged at diametrically opposite sides of the nozzle tip, are connected by and support a bridge 11, which extends across the tip opening to divide the steam blast, and is turned downwardly and formed into a stepped blade 13—15. The center portion 13 has a downwardly directed knife edge 14, and portions 15, at the ends of the center portion, are also provided with downwardly directed knife edges, in order to divide and spread the steam blast and increase the drawing force thereof according to the depression of the bridge. When the bridge 11 is in its lowermost position it will be supported by its end edges 16 resting on the top of the nozzle tip; it being apparent that when the bridge is in its lowermost position, the knife blades will divide the blast within the tip to increase the draft to a maximum and thereby effectively tear and stir up the fire when feeding with bad coal, or when the fire shows signs of getting dirty, clinkering, etc., and it is also apparent that the draft may be regulated by elevating the bridge to different points for securing the desired draft, and that the bridge may be raised entirely out of the nozzle when a low draft is desired.

At the front of the tip 3 is an outstanding lug 17, and revolvably mounted in and supported by the lug is a shaft 18, which ex-

tends outwardly from both edges of the lug and has one end projected through the smoke arch 19 where it carries an actuating arm 20, which is operable by means, presently described, from the engine cab.

Secured to the shaft 18 at opposite sides of the lug, preferably by set screws 21, are collars 22 which anchor the shaft against longitudinal movement while not interfering 10 with rotary movement thereof, and also fixed to the shaft outwardly from the collars 22 and preferably by the set screws 23, are the hubs 24 of arms 25, which latter extend across the sockets in the wings 3 and have 15 slots 26 therein through which pins 27, that are rigidly mounted on the posts 9 and extend outwardly through the sockets 8, project loosely so that the slotted arms may slide over the pins.

20 The slot 26 in each of the arms 25 is beveled outwardly at its ends in order to form free outlets for cinders that may accumulate within the slot, and thereby prevent stoppage of the slot that might interfere with 25 the full travel of the arm over its pin and limit the vertical adjustment of the bridge.

The arm 20 at the outer end of the shaft 18 projects between spaced stops 29 that are mounted on and project from the side of the 30 smoke arch in order to limit the movement of the arm and relieve the lever and bridge mechanism from strain.

Pivotedly connected with the outer end of the arm is a rod 30 which is formed in sections and provided with adjusting sleeves 31 whereby the length of the rod may be varied to regulate the lift of the bridge when moved by the rod handle 32 which is connected with the outer end of the rod.

40 The handle 32 comprises a latch bar member 33, which extends through a guide bracket 34 having an upwardly projecting latch tooth 35 thereon adapted for projection into the notches 36 in the lower edge of the bar, so that the bar and rod may be held in an adjusted position to retain the bridge at a proper elevation relative to the nozzle tip.

The bracket 34 preferably comprises an 50 arm 37, which is mounted on and projects from the smoke arch and has the tooth 35 formed integrally therewith; the guide part 38 comprising a U-shaped rod, which is mounted on the bracket and projects above the tooth, as illustrated.

In using my improvement, presuming the parts to be constructed and assembled as described, should the fire clinker or choke because of bad coal or otherwise, the bridge 60 may be lowered into the nozzle tip by manipulation of the latch rod from the engine cab, so that the blast is divided and restricted in the nozzle to effect a stronger pull through the grates and fire that will 65 tend to clean the fire; the strength of the

pull being regulated by position of the bridge and the latch mechanism being so arranged that when the latch is at one position the bridge will be at its lowest point and when at other positions at other predetermined points in the nozzle, so that the fireman can determine the effect of the blast by the position of the latch; it being apparent that when the bridge is at its lowest point a wide diversion of the exhaust steam is effected, which causes the stack to be entirely filled with the escaping steam and produces considerable vacuum in the smoke arch that causes a sharp blast on the fire, and that at each successive higher step of 75 the bridge the steam is diverted or choked to a lesser degree until when the bridge is elevated to its highest point, a full opening of the nozzle is provided that produces no additional vacuum in the smoke arch because of 80 the presence of the bridge.

Having thus described my invention, what I claim as new therein and desire to secure by Letters-Patent, is:—

1. The combination with an exhaust nozzle, of a bridge crossing said nozzle and comprising blades arranged in vertically stepped relation, and means for raising or lowering the bridge. 90

2. The combination with an exhaust nozzle, of movable bridge supports at opposite sides of the nozzle, a bridge carried by said supports and comprising blades arranged in stepped relation across the nozzle, and means for raising or lowering the bridge. 100

3. The combination with an exhaust nozzle, of a bridge comprising a plurality of stepped blades, means for movably supporting the blades, whereby the latter may move into or from the nozzle, and mechanism for 105 actuating the supporting means.

4. The combination with an exhaust nozzle, of posts slidably mounted at opposite sides of the nozzle, a bridge carried by said posts and comprising blades of different 110 length and arranged in stepped relation across the nozzle, and means for actuating said posts to raise or lower the bridge relative to the nozzle.

5. The combination with a nozzle, of 115 posts slidably mounted at opposite sides of the nozzle and adapted for longitudinal movement relative thereto, a bridge extending across the nozzle and mounted on said posts, said bridge comprising a suspended 120 blade having its ends set in from the posts to form a seat for the bridge on the edge of the nozzle, a second blade suspended from and set in from the ends of the first blade, and means for actuating the posts to vary the projection of the blades into and from the nozzle. 125

6. The combination with a nozzle having 130 outwardly-opening, vertical grooves in its outer face, posts slidably mounted in said

grooves and having beveled lower ends, a bridge carried by said posts, and means for raising and lowering the bridge.

7. The combination with a nozzle having 5 outwardly-opening, vertical grooves in its outer face, posts slidably mounted in said grooves and having outwardly and upwardly beveled lower ends, a bridge carried by said posts, and means for raising and 10 lowering the bridge.

8. The combination with a nozzle having grooves in its outer face, of posts slidably mounted in said grooves and having longitudinal grooves in their side faces, forming 15 cleaning channels in the nozzle grooves, a bridge carried by said posts, and means for shifting the bridge, for the purpose set forth.

9. The combination with a nozzle having 20 longitudinal wings provided with outwardly opening grooves, posts slidably mounted in said grooves and having longitudinal grooves on their sides facing the sides of the wings, a bridge carried by said posts, 25 and means for actuating the posts.

10. The combination with a nozzle having a pair of opposite longitudinal grooves in its exterior faces, posts slidably mounted in the grooves and having longitudinal 30 grooves in their side faces, and having outwardly and upwardly inclined lower ends, a bridge carried by the posts and extending across the nozzle, and means for actuating

the posts to vary the elevation of the bridge relative to the nozzle. 35

11. The combination with a nozzle having longitudinal wings on its opposite faces provided with outwardly opening longitudinal grooves, posts slidably mounted in the grooves and having longitudinal grooves in 40 their side faces, and having outwardly and upwardly inclined lower ends, a bridge carried by the posts and extending across the nozzle, cross pins mounted on the posts and projecting through said wing grooves, an 45 actuating shaft and slotted arms fixed on the shaft and operatively connected with the pins, means for actuating said shaft, and means for actuating said posts to vary 50 the elevation of the bridge relative to the nozzle.

12. The combination with a nozzle having wings on opposite sides thereof provided with outwardly opening grooves, of 55 posts slidably mounted in the wing grooves, a bridge carried by said posts, a rotatable shaft, arms carried by said shaft and each having a slot in its free end adjacent the wing grooves; the said slot being beveled outwardly to form a flared mouth; pins fixed to the posts and projected through the wing grooves and arm slots, and means for actuating the shaft.

In testimony whereof I affix my signature.

FREDERICK MERTSHEIMER.
